By: Noratio E. Bellone

Attorney,

UNITED STATES PATENT OFFICE.

FREDERICK S. BENEDICT, OF CRANSTON, RHODE ISLAND.

SAFETY GUARD.

Application filed March 7, 1922. Serial No. 541,765.

To all whom it may concern:

Be it known that I, FREDERICK S. BENEDICT, a citizen of the United States, residing at Cranston, in the county of Providence and State of Rhode Island, have invented 5 certain new and useful Improvements in Safety Guards, of which the following is a specification.

My invention relates to safety guards for 10 pulleys and belts.

The essential objects of my invention are to conform to the compulsory requirements of liability insurance company standards including the avoidance of an opening greater 15 than one-half an inch within four inches of the part guarded; to provide a single structure adapted for use upon pulleys of varying sizes and in different or changed locations and upon various machines, and upon 20 belts disposed vertically, or inclined to the right or left, or converging or diverging; to enable standardization of parts, minimize expense of construction, and facilitate application to the parts to be protected.

25 To the above ends essentially my invention consists in such parts and in such combinations of parts as fall within the scope of the appended claims.

In the accompanying drawings which 30 form a part of this specification,

Figure 1 is a perspective view of a guard embodying my invention,

Figure 2, a vertical central section of the same showing in side elevation a pulley and 35 a belt enclosed thereby,

Figure 3, a rear elevation of the same,

Figure 4, a section of the guard on line 4-4 of Figure 2, and

Figure 5, a partial section, corresponding 40 with that of Figure 2, of another position of a belt enclosing member.

Like reference characters indicate like parts throughout the views.

In its preferred form of embodiment my 45 device comprises a drum 7 and tangentially disposed sectional tubes or wings 8 pivotally attached thereto. The drum serves as a housing for a pulley 9 mounted on a shaft 10, and the tubes constitute closures for a 50 belt 11 engaging the pulley. In detail the drum comprises front and rear head end plates 13 provided with central openings 14 and spaced peripheral lugs 16 provided with 55 perforations 17 to receive bolts or tie rods 18, each having a squared head 19 and a thread 20 engaged by a nut 21. The side 22

of the drum, which is cylindrical in shape, may be engaged with the heads in any desired manner. In this instance it comprises two spaced sections consisting of a semi-circular bottom section 23, and an arcuate top section 24 spaced at both ends from the first section forming resultant lateral openings 25. Peripheral lugs 27 on opposite ends of these sections register with the lugs 16 and have perforations 26 through which pass the rods 18. By the described means the parts of the drum are readily assembled and disassembled. One or both of the end plates 13 may have a radial opening 29 to receive a removable filling strip 30 fastened in this case by transversely disposed spaced metal plates 32 fast to the strip and projecting laterally therefrom, and provided in their extended portions with slots 34 adapted to loosely receive pins 35 in the end plate. The opening 29 which extends from the periphery of the end plate to the opening 14 admits passage of a shaft 10 to the latter, after which the opening 29 is closed by the 80 filler strip.

Loose upon diametrically opposite rods 18, disposed in the same horizontal plane adjacent the lower ends of the openings 25 are hinge sleeves 37 upon depending hinge 85 straps 38 fast to the members 8 by pins 39 or otherwise. The described parts constitute hinge members for the belt housing members or arms 8. As illustrated the latter include lower and upper tubular sections 41 and 42 of oblong rectangular cross section, the latter telescoping in the former. Each section 41 comprises an outer wall 44 to which the hinge is attached, an inner wall 45, and front and rear walls 46 and 47. The 90 rear wall 47 has a central longitudinal slot 48 extending throughout its length to permit the admission of a belt 11. The lower portion of each wall 45 is cut away to form an opening 50. In this instance the four 95 corners of sections 41 are reinforced by angle irons 51.

The sections 42 are a sliding fit in the sections 41 and are vertically adjustable by any convenient means. In this instance the adjusting means consists of a removable plug 53 insertable in a perforation 54 in a wall of the section 41, and in one of a vertical series of perforations 55 registering with the first perforation. The rear walls 58 of the 110 section 41 are provided with central longitudinal slots 59 extending throughout their

lengths and registering with the slots 48 for admission of a belt 11. The corners of sections 42 are reinforced by angle irons 60. The vertical adjustability of the sections are 5 useful in fulfilling insurance requirements of sheathing the belts any given height above the floor.

Slidably mounted upon the inner faces of the inner walls 45, and closing the upper 10 portions of the openings 50 are slides or plates 62 terminating in hinge sleeves 63 engaging pintles 64 embraced by hinge sleeves 66 on arcuate slides or plates 67 slidably engaging the inner face of the drum 15 section 24, and closing the upper portions of the openings 25. The slides 62 are pressed into contact with the walls 45 by resilient guiding fingers 69 overlapping the slide and fast at their upper ends by rivets 20 70 to the walls. Spaced plates 71 are fastened by rivets 72 in their central portions to the section 24 and their end portions constitute resilient guide fingers 74 which overlap the adjacent inner end portions of the 25 plates 67.

The lower portions of the sections 41 pass through the openings 25 and into the drum, the walls 44 only being tangential thereto. The lower portions of the walls 46 and 47, by 30 virtue of the openings 50, straddle the pulley 9 and slide freely in contact with or adjacent the inner faces of the drum ends. Hence nothing impedes an inwardly inclined 35 position of the sectional arms 8 such as shown in broken lines in Figure 5.

It will be observed that changing the inclination of one or both the sectional arms 8 inwardly or outwardly leaves no resultant 40 openings in either the cut away portions of the drum or of the sections 41, because of the 45 slidable character of the pivoted plates 62 and 67.

If desired auxiliary means may be employed to assist to maintain the arms 8 in 45 fixed relation to each other after being applied to the machine. One such means consists, as shown in Figure 1, of a flat rod or latch 76 pivoted at one end to a pin 77 on one section 41 and provided near its other 50 end with a series of lateral cavities 78 in its lower edge in one of which registers a pin 80 fast in the other section 41.

I claim:—

1. In a machine safety guard, a drum provided with peripheral openings, tubular arms pivotally supported on the drum adjacent the openings, and plates slidably mounted on the drum across the openings carried by the arms.

60 2. In a machine safety guard, a drum provided with peripheral openings, tubular arms pivotally supported on opposite sides of the drum and provided with lateral openings adjacent the drum, plates slidably 65 mounted on the drum across the peripheral

openings, and plates slidably mounted on the arms across the lateral openings pivotally connected with the first mentioned plates.

3. In a machine safety guard, a drum provided with peripheral openings, tubular 70 arms pivotally supported on the drum adjacent the openings, guides fast to the drum, slidable plates engaging the guides carried by the arms and movable across the openings.

75 4. In a machine safety guard, a drum provided with peripheral openings, tubular arms pivotally supported on opposite sides of the drum provided with lateral openings adjacent the drum, guides fast to the drum, 80 slidable plates engaging the guides movable across the peripheral openings, guides fast to the arms, and slidable plates engaging the last mentioned guides movable across the lateral openings pivotally attached to 85 the first mentioned plates.

5. In a machine safety guard, a drum comprising a body, end plates engageable with the body, peripheral projections on the end plates, peripheral projections on the 90 body, and bolts connecting the body and end plates through the projections, tubular arms, and hinge members carried by the arms engaging the bolts on opposite sides of the drum.

95 6. In a machine safety guard, a body comprising a semi-circular bottom section and an arcuate top section spaced from each other to constitute openings, end plates, a bolt connecting the top section with the end 100 plates, bolts connecting the bottom section with the end plates, and tubular arms pivotally mounted on the last mentioned bolts movable into and out of the openings.

7. In a machine safety guard, a drum 105 provided with a radial opening, tubular arms carried by the drum, and a guard strip detachably mounted in the arm across the opening.

8. In a machine safety guard, a drum 110 provided with a radial opening, tubular arms carried by the drum, pins in the drum beside the opening, a guard strip in the opening, and cross pieces on the strip provided with cavities adapted to receive the 115 pins.

9. In a machine safety guard, a drum, tubular arms pivotally supported on opposite sides of the drum, a latch pivotally mounted on one arm and provided with a 120 longitudinal series of cavities, and a projection on the other arm adapted to register in one of the cavities.

10. In a machine safety guard, a drum, tubular sections pivotally supported on opposite sides of the drum provided with longitudinal slots, and tubular sections telescoping in the first sections and provided with longitudinal slots registering with the 125 slots in the first sections.

11. In a machine safety guard, a drum, series of cavities, and a projection in the
tubular sections pivotally mounted on the other of said sections adapted to register
drum provided with longitudinal slots, tu- in said cavities.
5 bular sections slidably mounted in the first In testimony whereof I have affixed my
sections provided with longitudinal slots registering with the first slots, one of said
sections being provided with a longitudinal
